CLAIM

The ornamental design for a wand, as shown and described.

DESCRIPTION

FIG. 1 is a perspective view of the new design for a wand;

FIG. 2 is another perspective view thereof;

FIG. 3 is a front side view thereof;

FIG. 4 is a right side view thereof, in which the left side view is a mirror image thereof;

FIG. 5 is a back view thereof;

FIG. 6 is a top view thereof; and,

FIG. 7 is a bottom view thereof.

The broken lines shown in the drawings illustrate portions of the article and form no part of the claimed design.

1 Claim, 4 Drawing Sheets
